SWITCH & SIGNAL COMPANY, OF SWISSVALE, PENNSYLVANIA, A CORPORATION
OF PENNSYLVANIA.

RAILWAY SIGNALING.

1,359,131.

Specification of Letters Patent.

Patented Nov. 16, 1920.

Application filed May 8, 1918. Serial No. 233,209.

To all whom it may concern:

Be it known that I, HERBERT A. WALLACE, a citizen of the United States, residing at Pittsburgh, in the county of Allegheny and State of Pennsylvania, have invented certain new and useful Improvements in Railway Signaling, of which the following is a specification.

My invention relates to railway signaling, and particularly to signaling systems of the type in which two relays are connected with the track rails adjacent the ends of a stretch of track and are energized by current supplied to the rails at an intermediate point in the stretch.

I will describe certain forms of apparatus embodying my invention and will then point out the novel features thereof in claims. In the accompanying drawings, Figure 1 is a diagrammatic view showing one form of railway signaling system embodying my invention. Figs. 2 and 3 are diagrammatic views showing modifications of the means shown in Fig. 1 for controlling the polarity of the current supplied to the track rails, and also embodying my invention. Fig. 4 is a fragmental view showing a modification of part of the apparatus shown in Fig. 2. Figs. 5, 6 and 7 are views showing means for supplying signaling current to the track rails which may be substituted for the means shown in Figs. 1, 2 and 3.

Similar reference characters refer to similar parts in each of the views.

Referring first to Fig. 1, the reference character E designates the track rails of a stretch of railway track A—B between two passing sidings C and D. The rails of the stretch A—B are electrically isolated from the rails of the adjoining sections by insulated joints 24. Located adjacent the ends of the stretch A—B are two track relays R' and R², each of which, as here shown, comprises a track winding 2 and a line winding 3. The track winding 2 of each relay is connected with the track rails, and the line winding 3 is constantly supplied with alternating signaling current by means of a transformer T' or T². To simplify the drawing, the sources of current are not illustrated, but it is understood that the primary windings of transformers T' and T², as well as the primary winding of transformer T³,

which supplies current to the track rails as hereinafter explained, are all connected with the same source of alternating current.

Alternating signaling current for the track windings of the relays is supplied to the track rails at or near the middle of the stretch by any suitable means. As shown in Fig. 1, this is accomplished by a single transformer T⁵, the secondary of which is connected with the rails and the primary of which is supplied with alternating signaling current of one instantaneous polarity or the other by means hereinafter explained. This means for supplying the signaling current to the track rails may be replaced by other suitable means, such for example as by any one of the arrangements shown in Figs. 5, 6 and 7, wherein the rails are divided at or near the middle of the stretch A—B by insulated joints 24^a, and signaling current is supplied to each of the track sections so formed. In Fig. 5, current is supplied to the two sections in multiple from the secondary of transformer T⁵, suitable voltage reducing means such as resistances being interposed in the connections to the track rails as shown. In Fig. 6, the transformer T^{5a} is provided with two secondary windings, one for each track section. In Fig. 7, two transformers T^{5b} are provided, one for each track section.

Each track relay R' and R² comprises two contacts 4 and 5, which contacts occupy intermediate or vertical positions when the relay is deenergized, that is, when current is cut off from either or both of the relay windings, and which contacts are swung to the left or to the right according as the instantaneous polarity of the current in the track winding 2 is normal or reverse with respect to the polarity in winding 3. Each relay is, consequently, responsive to reversals of the instantaneous polarity of the current in the track rails.

Located adjacent the ends of the stretch are two end signals S' and S², for governing traffic through the stretch in opposite directions. Each of these signals is adapted to indicate "stop," "caution" and "proceed," and is provided with a caution circuit and a proceed circuit as hereinafter explained.

Located on opposite sides of the middle of the stretch are two intermediate signals

S^3 and S^4 which are controlled in the following manner:

Signal S^3 is controlled by a relay F^3 , which in turn is controlled by contact 5 of relay R^2 . The circuit for relay F^3 is from transformer T^2 , through wire 37, contact 5, wire 38, relay F^3 , and wires 39, 40, 41 and O to transformer T^2 . Relay F^3 is therefore energized whenever relay R^2 is energized in either normal or reverse direction, and deenergized whenever relay R^2 is deenergized. The caution indication circuit for signal S^3 is from transformer T^6 , through wires 42 and 43, contact 44 of relay F^3 , wire 45^a, wire 45, signal S^3 , wires 46, 47, O and 41 to transformer T^6 . The proceed indication circuit for this signal is the same as the caution circuit up to and including wire 45^a, and it then passes through wire 80, contact K' operated by the signal to the right of siding D corresponding to signal S' , wire 81, mechanism of signal S^3 , and wires 46, 47, O and 41 to transformer T^6 . Contact K' is closed when the signal by which it is controlled indicates proceed or caution, but open when such signal indicates stop. It will be seen, therefore, that whenever track relay R^2 is deenergized, signal S^3 will be in the stop position, and that when this relay is energized, the signal will indicate caution or proceed according to the position of the signal to the right corresponding to signal S' . Signal S^4 is controlled in a similar manner by a relay F^4 , which in turn is controlled by contact 5 of relay R' , so that when relay R' is deenergized signal S^4 is in the stop position. This signal is also controlled by a contact corresponding to contact K^2 on signal S^2 .

Signal S' is normally controlled by relay F^3 and by track relay R' , the control being such that this signal indicates proceed or caution according as relay R' is energized in normal or reverse direction. The proceed indication circuit for this signal is from transformer T^6 , through wires 42, 48, and 49, back point of contact 50 of a relay H^4 , wires 51 and 52, contact 53 of relay F^3 , wires 54 and 55, contact 4 of relay R' , wire 8, signal S' , wires 9, O, and 41, to transformer T^6 . This circuit is closed only when contact 4 of relay R' is swung to the left, that is, only when this relay is energized in "normal" direction. The caution circuit is the same as the proceed circuit up to and including contact 4, and it then passes through wire 10 to signal S' and returns through wires 9, O and 41 to transformer T^6 . The caution circuit is therefore closed only when contact 4 of relay R' is swung to the right, that is, when this relay is energized in "reverse" direction. It will be seen that so far as the apparatus thus far described is concerned, signal S' will be in

the stop position when relay F^3 is deenergized, that is, when relay R^2 is deenergized.

Signal S^2 is similarly controlled by relays F^4 and R^2 so that this signal normally indicates stop when relay R' is deenergized, and caution or proceed according as relay R' is energized in reverse or normal direction.

The circuit for signal S' is provided with a branch around contact 53 of relay F^3 , which branch passes from wire 51, through contact 56 of an auxiliary relay H^3 , and wire 57 to wire 55. It follows, therefore, that when relay H^3 is energized, signal S' may indicate caution even though relay R^2 , and, consequently, relay F^3 , are deenergized. It cannot indicate proceed under these conditions for reasons which will appear hereinafter.

The circuit for signal S^2 is provided with a similar branch around the contact 68 of relay F^4 which controls this circuit, this branch including a contact 69 of an auxiliary relay H^4 . It follows then that when relay H^4 is energized, signal S^2 may indicate caution even though relay R' , and, consequently, relay F^4 are deenergized.

Auxiliary relay H^3 is provided with a pick-up circuit which is closed only when relay F^3 is deenergized, this circuit being from transformer T^6 , through wires 42 and 48, back point of contact 58 of relay F^4 , wire 59, front point of contact 60 of relay F^3 , wire 61, relay H^3 , wire 62, back point of contact 63 of relay H^4 , and wires 64 and 41 to transformer T^6 . It will be seen, therefore, that this circuit is closed only while relays F^4 and H^4 are deenergized. Relay H^3 is provided with a holding circuit which maintains this relay in the energized condition as long as relay F^3 is deenergized, this circuit being from transformer T^6 , through wires 42, 48 and 65, front point of contact 66 of relay H^3 , wire 67, back point of contact 60 of relay F^3 , wire 61, relay H^3 , wire 62, back point of contact 63 of relay H^4 , and wires 64 and 41 to transformer T^6 .

It follows from the foregoing that when a train moving toward the right enters the stretch A-B, the consequent opening of relay F^4 closes the pick-up circuit for relay H^3 , and that this relay remains energized during the passage of the train through the entire stretch, because its holding circuit is closed when relay F^3 is deenergized, that is, while the train is in the right-hand end of the stretch. Consequently, after such train has passed the middle of the stretch and relay R' has become energized, signal S' may move to the caution position, even though relay F^3 , which normally controls this signal, is open.

The auxiliary relay H^4 is provided with similar circuits whereby this relay becomes energized when a train moving toward the

left enters the stretch A—B, and continues to be energized as long as the train occupies any part of the stretch.

The polarity of the track circuit is controlled by two pole-changers Q^3 and Q^4 operated by the two intermediate signals S^3 and S^4 , respectively. These pole-changers are connected in series and serve to control the polarity of the current supplied to transformer T^5 from a transformer T^3 . When both of the intermediate signals indicate caution or proceed, current of normal polarity is supplied to the track circuit, the circuit for the primary of transformer T^5 then being from the right-hand terminal of the secondary of transformer T^3 through wire 70, pole-changer Q^3 , wire 71, pole-changer Q^4 , wire 72, primary of transformer T^5 , wire 73, pole-changer Q^4 , wires 74, O and 47, pole-changer Q^3 , and wire 75 to the left-hand terminal of transformer T^3 . Assuming that the instantaneous polarity of the right-hand terminal of the secondary of transformer T^3 is positive, as indicated by the (+) sign on the drawing, the polarity of the primary of transformer T^5 at the same instant will be such that the left-hand terminal of the primary of this transformer is positive. This is the normal polarity of the track circuit. It is understood that pole-changer Q^3 occupies the position in which it is shown when signal S^3 is in either caution or proceed position, but that this pole-changer is reversed when the signal is in stop position; pole-changer Q^4 is controlled in the same manner by signal S^4 . If, then, either signal S^3 or S^4 moves to the stop position, the corresponding pole-changer will be reversed, so that the polarity of the track circuit will be reversed, whereby both track relays R' and R^2 will become reversely energized.

The operation of the system shown in Fig. 1 is as follows:

When a train moving toward the right enters stretch A—B, it opens track relay R' , which in turn opens relay F^4 , so that signals S' , S^2 and S^4 move to the stop position. The opening of relay F^4 causes auxiliary relay H^3 to become energized. The movement of signal S^4 to the stop position, of course, reverses the polarity of the track circuit, but this has no immediate effect on the signals. As the train approaches the middle of the stretch, it opens relay R^2 , which in turn de-energizes relay F^3 , whereby the holding circuit for relay H^3 becomes closed. The opening of relay F^3 also causes signal S^3 to move to the stop position. As the train passes beyond the middle of the stretch, relay R' becomes energized, and this in turn causes relay F^4 to become energized, so that signal S^4 moves to the caution or proceed position, depending on the position of the signal to the left corresponding to signal S^2 . Signal

S^3 being in the stop position, current of reverse polarity is supplied to the track circuit, so that relay R' is energized in the reverse direction, whereby signal S' moves to the caution position. A following train moving toward the right can then enter stretch A—B with notice that the stretch is already occupied by another train moving in the same direction. Assuming that no such second train enters the stretch, however, when the first train passes out of the stretch relay R^2 will become energized, thus causing relay F^3 to become energized, whereupon signal S^3 moves to the caution position and the holding circuit for relay H^3 becomes opened. Both signals S^3 and S^4 now being either at caution or proceed, the polarity of the track becomes normal, so that relay R' becomes energized in the normal direction, whereby signal S' moves to the proceed position. Signal S^2 , of course, returns to its proceed position for the same reason.

Referring now to Fig. 2, the means here shown for controlling the polarity of the track circuit comprises two transformers T^3 and T^4 , and two contacts 15 and 17 operated by signals S^3 and S^4 respectively. It is of course understood that the primary windings of transformers T^3 and T^4 are connected with a suitable source of signaling current which is not shown in the drawing. The voltage across the end terminals of the secondary of transformer T^3 is double the voltage across the secondary of transformer T^4 , and the secondary of transformer T^3 is provided with a middle terminal which is connected with a wire 21. For the purpose of showing clearly the instantaneous relative polarities, I will assume that the left-hand end terminal of transformer T^3 is positive and that the left-hand terminal of transformer T^4 is also positive. When both signals S^3 and S^4 indicate proceed or caution, transformer T^5 is supplied with alternating signaling current from transformer T^3 , the circuit being from the left-hand end terminal of transformer T^3 , through wire 14, contact 15, wire 16, contact 17, wire 18, primary of transformer T^5 , and wires 19, O and 21 to the middle point of the secondary of transformer T^3 . The left-hand terminal of the primary of transformer T^5 is then positive, this being the normal instantaneous polarity of the track circuit. If, now, signal S^3 changes to stop indication, the instantaneous polarity of the current supplied to transformer T^5 is reversed, the circuit then being from the right-hand end terminal of the secondary of transformer T^2 , through wire 22, contact 15, wire 16, contact 17, wire 18, primary of transformer T^5 , wires 19, O and 21, to the middle point of the secondary of transformer T^3 . The instantaneous polarity of the left-hand terminal of the primary of transformer T^5 then becomes negative, so

that the instantaneous polarity of the track circuit is reversed. I will now assume that signal S^4 changes to the stop position. Transformer T^3 is then disconnected from transformer T^5 by contact 17, but this contact connects transformer T^5 with transformer T^4 , the circuit being from the right-hand terminal of the secondary of transformer T^4 , through wire 23, contact 17, wire 18, 10 primary of transformer T^5 , wires 19, O and 13, to the left-hand terminal of the secondary of transformer T^4 . The left-hand terminal of the primary of transformer T^5 is then of negative instantaneous polarity, so that the 15 polarity of the track circuit is reverse.

If desired, the single transformer T^3 with a tap at the middle point of the secondary may be replaced by two transformers T^{3a} arranged as shown in Fig. 4. I do not desire 20 to limit myself, however, to either of these structures, as any suitable means may be employed for reversing the polarity of wire 16 by circuit controller 15.

Referring now to Fig. 3, in the arrangement here shown the polarity of the track circuit is governed by a pole-changing relay P , which connects the primary of transformer T^5 with the secondary of transformer T^4 in one direction or the other, depending 30 on whether the relay P is energized or de-energized. In the arrangement here shown, the polarity of the track circuit is normal when relay P is energized, and reverse when this relay is de-energized. The circuit for 35 the primary of transformer T^5 , when relay P is energized, is as follows: from secondary of transformer T^4 , through wire 25, front point of contact 26, wire 27, primary of transformer T^5 , wires 28, O 13, and 29, front 40 point of contact 30, wire 31, to transformer T^4 . The circuit for the primary of transformer T^5 , when relay P is de-energized, will be apparent from the drawing. It will, of course, be understood that the primary 45 winding of transformer T^4 is connected with the source of alternating signaling current.

Relay P is controlled by signals S^3 and S^4 through the medium of contacts 15 and 17, the control being such that this relay is energized when both signals indicate caution or proceed, but de-energized when either signal indicates stop. Relay P is energized from the secondary of transformer T^3 , the primary of which is connected with the 50 source of signaling current. The circuit for relay P is from the secondary of transformer T^3 , through wire 32, contact 15, wire 33, contact 17, wire 34, relay P , wires 35, 55 13, O and 36, to the transformer T^3 . This 60 circuit is, of course, opened at either contact 15 or 17 when signal S^3 or S^4 changes to the stop position.

Although I have herein shown and described only a few forms of apparatus embodying my invention, it is understood that

various changes and modifications may be made therein within the scope of the appended claims without departing from the spirit and scope of my invention.

Having thus described my invention, what I claim is:

1. In combination, a stretch of railway track, a source of current reversibly connected with the track rails adjacent the middle of the stretch, two relays receiving energy from the track rails adjacent the ends of the stretch respectively and each responsive to reversals of current, and two signals for the stretch one adjacent each end and controlled by said relays respectively. 80

2. In combination, a stretch of railway track, a source of current reversibly connected with the track rails adjacent the middle of the stretch, two relays receiving energy from the track rails adjacent the ends of the stretch respectively and each responsive to reversals of current, and a signal controlled by each of said relays. 85

3. In combination, a stretch of railway track, two relays receiving energy from the track rails adjacent the ends of the stretch respectively and each responsive to reversals of current in the rails, two end signals adjacent the ends of the stretch respectively each controlled by the adjacent relay and indicating clear or caution according as the relay is energized in normal or reverse direction, two intermediate signals on opposite sides of the middle of the stretch and each controlled by the track relay on the far side of the middle of the stretch, and means controlled by said intermediate signals for supplying current to the track rails adjacent the middle of the stretch in normal direction when both intermediate signals indicate proceed or caution and in reverse direction when either intermediate signal indicates stop. 10

4. In combination, a stretch of railway track, two relays receiving energy from the track rails adjacent the ends of the stretch respectively and each responsive to reversals of current in the rails, two end signals adjacent the ends of the stretch respectively each controlled by the adjacent relay and indicating clear or caution according as the relay is energized in normal or reverse direction, two intermediate signals on opposite sides of the middle of the stretch and each controlled by the track relay on the far side of the middle of the stretch, and means controlled by said intermediate signals for supplying current to the track rails adjacent the middle of the stretch in normal direction when both intermediate signals indicate proceed or caution and in reverse direction when both intermediate signals do not indicate proceed or caution. 11

5. In combination, a stretch of railway track, two relays receiving energy from the

- track rails adjacent the ends of the stretch respectively and each responsive to reversals of current in the rails, means for signaling controlled by said relays, a signal located 5 between an end of the stretch and the middle, and means controlled by said signal for supplying current to the track rails adjacent the middle of the stretch in normal direction when the signal indicates proceed and in 10 reverse direction when the signal indicates stop.
6. In combination, a stretch of railway track, two relays receiving energy from the track rails adjacent the ends of the stretch 15 respectively and each responsive to reversals of current in the rails, means for signaling controlled by said relays, two signals located on opposite sides of the middle of said stretch, two pole-changers one for each signal, each pole-changer being in normal or 20 reverse position according as the corre-
- sponding signal indicates proceed or stop, and means including said two pole-changers in series for supplying signaling current to the track rails adjacent the middle of the stretch. 25
7. In combination, a stretch of railway track, two relays receiving energy from the track rails adjacent the ends of said stretch respectively and each responsive to reversals of current, means for supplying current of normal or reverse polarity to the track rails adjacent the middle of said stretch, and means for signaling controlled by said relays. 30
- 35

In testimony whereof I affix my signature in presence of two witnesses.
